UNITED STATES PATENT OFFICE

165,948

WAIST GIRDLE

Ruth D. Tys, Lynwood, Calif.

Application October 8, 1951, Serial No. 16,867

Term of patent 14 years

(Cl. D20—2)

To all whom it may concern:

Be it known that I, Ruth D. Tys, a citizen of the United States, residing at Lynwood, State of California, have invented a new, original, and ornamental Design for a Waist Girdle, of which the following is a specification, reference being had to the accompanying drawing, forming a part hereof.

Fig. 1 is a front elevational view of a waist girdle, showing my new design in an extended position.

Fig. 2 is a front perspective view thereof in a partially closed position.

Fig. 3 is a rear perspective view thereof in a completely closed position.

The characteristic feature of my new design resides in the combination, on the waist girdle disclosed, of an elongated main body having at the ends thereof trapezoidal closing flaps arranged in completely overlapping relation when the garment is closed, whereby reversed, short, wide V-shapes are presented at the longitudinal

edges of the flaps, the main body further having an elongated border portion at the upper longitudinal edge thereof, with spaced strips extending transversely across the body, all as shown.

I claim:

The ornamental design for a waist girdle, as shown and described.

RUTH D. TYS.
